THERMOPROTECTIVE SWITCH

David F. Moyer, Dayton, Ohio, assignor to General Motors Corporation, Detroit, Mich., a corporation of Delaware

Application November 13, 1952, Serial No. 320,275

7 Claims. (Cl. 200—116)

1

This invention relates to an improved protective control device for automatically opening the electric circuit to an electrical device, such as an electric motor, whenever overloads occur on the electrical device.

An object of the invention is to provide a protective control device that has a short time limit for opening an electric circuit under overload conditions of an electrical apparatus, and which device can be utilized with electric apparatus over a wide range of current usage.

In previous protective control devices it has been considered essential to vary the construction of the heat-sensitive element of a protective control device so that it might accept varying current loads. Thus, it has been the usual practice to calibrate carefully the electric heaters or other current-sensitive devices used in protective control devices so that they could be matched accurately to the current rating of the electrical device to give the desired degree of overload protection to the electrical device.

In this invention, however, the apparatus is constructed and arranged in a manner that a single electrical component that is current sensitive can be used to give satisfactory overload protection to a wide range of electrical devices drawing widely varying currents.

The foregoing is accomplished in this invention by constructing the apparatus to vary the mechanical relationships of the tripping mechanical components of the protective control device while retaining the tripping time relatively constant, thus eliminating the necessity of accurately calibrating heat-sensitive or current sensitive devices that vary widely in manufacturing tolerances.

It is, therefore, an object of this invention to provide a protective control device, particularly for electric motors, wherein the position of the mechanical components of the tripping mechanism of the device can have their relative positions changed to effect substantially constant time lag in operation of the tripping mechanism under different current usage.

It is a further object of the invention to accomplish the aforesaid object by altering the pivot connection of a trip lever relative to a heat or current sensitive device.

It is also an object of the invention to provide a protective control device incorporating the features of the aforesaid object wherein an electric shunt is provided around the current-sensitive tripping mechanism of the device to provide for usage of a single device on a wide range of current loads.

2

Further objects and advantages of the present invention will be apparent from the following description, reference being had to the accompanying drawings wherein a preferred embodiment of the present invention is clearly shown.

In the drawings:

Fig. 1 is a side elevational view of a protective control device constructed in accordance with the invention and including a diagrammatic electric circuit in which to provide suitable protection for an electric motor;

Fig. 2 is a cross sectional view taken along the lines 2—2 of Fig. 3, but illustrating certain of the parts of the device in dot-and-dash line for the purpose of clarity;

Fig. 3 is a cross sectional view taken along the line 3—3 of Fig. 1;

Fig. 4 is an elevational view of one of the adjustment plates of the device which affects the current rating of the device;

Fig. 5 is an elevational view of another adjustment plate of the device;

Fig. 6 is a side elevational view of the plate in Fig. 5.

The apparatus of this invention includes a housing 10 constructed of electrical insulating material. The housing 10 has a chamber 11 that receives the actuating mechanism of the device.

The actuating mechanism consists of a rod 12 journaled in the walls 13 and 14 of the housing 10, the rod 12 projecting across the chamber 11. One end of the rod 12 carries a contact bar 15 that is urged against a shoulder 16 by means of a compression spring 17. A finger button 18 is mounted on the end of the rod 12 and retains the spring 17 in position between the button 18 and the contact bar 15.

Contacts 19 and 20 are secured to the wall 13 of the housing 10 for engagement by the contact bar 15 whereby to conduct current to an electrical apparatus, such as an electric motor.

The rod 12 has a reduced diameter extension 21 that extends through an opening 22 in an arm means 23, the arm means 23 forming one of the mechanical components of a tripping mechanism. The rod portion 21 engages the arm 23 at opposite sides of the opening 22, the arm 23 riding between knife edges 24 and 25 provided on the rod portion 21.

The arm 23 is supported at one end thereof by a pivot pin 26. The pivot pin 26 is in turn journaled in an opening 27 provided in a mounting plate member 30.

The mounting plate 30 is the second of two

mounting plates that cooperate to support the pivot 26 in a controlled linear position relative to a heat-sensitive bimetal detent member 31. The first mounting plate member is the plate 32 supported on the housing 10.

The mounting plate 32 is movably supported on the housing 10, with the fixed pivot pin 33 secured to a wall 34 of the housing. (See Fig. 3.) The plate 32 is rotatable about the fixed pivot 33 and is secured immovably relative to the housing 10 by means of a screw 35 in threaded engagement with the housing wall 34. An enlarged opening 36 is provided in the plate 32 to provide for limited rotative movement of the plate 32 about the fixed pivot pin 33.

The second mounting plate 30 has an opening 37 that fits over the fixed pivot 33. The plate 30 also carries a screw 38 that extends through an opening 39 into engagement with the threaded boss 40 of the plate 32, whereby to predominately position the plate 30 relative to the plate 32, and to provide for removal of the plate from the plate 32 under conditions and for reasons hereinafter described.

The arm 23 is spring urged in a clockwise direction (see Fig. 2) about the pivot 26 by means of a spring 41.

A current heat-sensitive detent member 31 is secured to the housing 10 by means of a fastening screw 28 and a conductor lug 43. The free end 44 of the current-sensitive, bimetal element 31 is attached to a flexible electric lead 45 that in turn is attached to a conductor lug 46. Thus, electric current is carried through the element 31 for rendering it current-sensitive to heating under the load drawn by the electrical device in circuit with the protective control device.

When the protective control device is in circuit closing position, the parts thereof assume the relative positions shown in Fig. 1 with the free end 47 of the arm 23 being engaged by the free end 44 of the detent 31 to hold the contact bar 15 upon the contacts 19 and 20.

With the protective control device in the position illustrated in Fig. 1 an electric circuit is closed through the contacts 19 and 20 to an electric motor 50 diagrammatically illustrated in the wiring circuit of Fig. 1.

The electric motor 50 consists of a running winding 51 and a starting winding 52. A speed responsive switch 53 is placed in circuit with the starting winding 52 for opening the starting winding when the motor approaches running speed.

Electric circuit to the motor 50 is thus made through the protective control device through the electric line 55, contacts 19 and 20, line 56, detent member 31, lead 45 and line 57 to the opposite side of the line 58.

In operation, when the motor 50 becomes overloaded for any reason, current carried by the detent member 31 causes excessive heating of the member 31 whereby it bends downwardly (see Figs. 1 and 2) to cause release of the arm 23. The arm 23 moves in a clockwise direction about pivot 26 as urged by the spring 41 to cause movement of the rod 12 in a left-hand direction and thereby open the circuit through the contacts 19 and 20. This results in breaking the circuit to the motor 50, or other electrical device arranged in series with the protective device.

The protective control device is manually reset after the overload is removed from the motor, removal of the overload allowing the bimetal 31 to cool, by moving the rod 12 in a right-hand

direction to reset the tripping mechanism comprising the arm 23 and the member 31.

The bimetallic detent member 31 when constructed to determined dimensions and of determined materials has a predetermined rate and extent of movement resulting from heating thereof to predetermined values. This is an accepted electrical characteristic of bimetal elements and therefore any given current-sensitive or heat-sensitive, bimetallic element will have the free end thereof moved a predetermined distance over a predetermined time interval when heat is applied to the bimetal at a given rate, either by an external source or by electric current flow through the bimetal. Thus, any specific mechanical arrangement of the bimetal element with a tripping arm can provide for only one timed release of the arm under any given set of circumstances. To provide for the same tripping time under a different current load requires an interchange of bimetal elements having different electrical characteristics. In this invention, however, a single bimetal element is used to carry a plurality of current values and still maintain substantially the same tripping time to provide overload protection for electrical devices having widely varying current ratings.

This is accomplished in the structure of this invention by controlling the linear dimension between the pivot 26 and the free end 44 of the bimetal 31. When the bimetal element 31 is at rest in its normal unflexed position, the pivot 26 can be positioned from the free end 47 of the bimetal 31 to provide for protection of an electrical device having low current rating. As the current rating of the device to be protected increases the pivot 26 of the arm 23 is moved linearly of the free end 44 of the bimetal 31 thereby giving a greater extension of the arm 23 beyond the free end of the bimetal member. However, since the current rating of the device being protected is increased, there will be a greater rate of movement of the bimetal member 31 because of the increased current flow through the member 31, resulting in a tripping time of the protective device of substantially the same value as when used in circuit with an electrical device of lower current rating.

The bimetal member 31 while having a rate of movement determined by the current flow through it which increases with increasing current flow, also has a relative maximum rate of movement beyond which increasing current flow through the bimetal has substantially no effect. Therefore, bimetal elements have a maximum utility beyond which they are no longer effective for response to increased current flow. Also, there is a maximum safe current flow that can be carried by a specific bimetal element. However, in this invention the effectiveness of the bimetal member 31 is retained for current ratings beyond its normal maximum safe current load by placing an electrical shunt 60 in parallel with the bimetal member 31 to carry a part of the current drawn by the electrical apparatus, such as the motor 50. The electrical shunt 60 thereby relieves the bimetal member 31 from a part of the total current carried. The arrangement is such that the maximum current carried by the bimetal is no more than the maximum safe current to which it is normally responsive at a maximum rate of movement. For example, the bimetal element 31 when used alone, will provide for thermal overload protection for electrical loads rated from about 4.8 amperes to 13 amperes. By placing an electrical

shunt 60 in parallel with the bimetal member 31 so that the bimetal carries only one-third of the total current, the bimetal element can be made to function at substantially the same rates as previously through a new range of from about 14 amperes to 40 amperes.

To accomplish changes in current rating of the protective control device, the mounting plate 30 is one of a series of plates in which each plate has the opening 27 for the pivot 26 positioned about the opening 37 at a different radial angle, for example, openings 65 and 66, shown in dotted lines in Fig. 4, to provide for different linear displacement of the pivot 26 relative to the free end 44 of the bimetal element 31. Thus, to adapt the protective control device of this invention to different current rating of electrical apparatus, it is merely necessary to remove the plate 30 from the device and replace it with another identical plate having the pivot opening 27 placed linearly different relative to the free end 44 of the bimetal 31.

The plate 32 provides for a factory adjustment of the protective control device. This is accomplished by placing a plate 30 in position upon the plate 32 with what may be termed a zero rating to which all protective devices are factory adjusted. The zero rating of the factory adjustment is occasioned by rotating plate 32 on the pivot pin 33 to adjust the free end 47 of the arm 23 relative to the free end 44 of the bimetal 31 whereupon the screw 35 is tightened and soldered to prevent subsequent tampering. Rating readjustment of the protective control device to match the current rating of an electrical device to be controlled thereby is then made by removing the factory adjustment plate 30 and replacing the same with a previously prepared rating plate 30 having a predeterminedly positioned pivot opening 27 to establish a predetermined displacement between the pivot 26 and the free end 44 of the bimetal 31 to give a predetermined time lag to the tripping mechanism according to the current drawn by the electrical device to be controlled.

While the embodiment of the present invention as herein disclosed constitutes a preferred form, it is to be understood that other forms might be adopted.

What is claimed is as follows:

1. A protective control device for automatically opening an electric circuit to an electrical device, comprising in combination, shiftable circuit breaking means for closing an electric circuit to render an electrical device operative, arm means engageable with said circuit breaking means to render the same active, pivot means for pivotal mounting of said arm means, heat sensitive detent means engageable with said arm means retaining the same in position for closing of said circuit breaking means and providing tripping means for release of said arm means to provide for actuation of said circuit breaking means, mounting plate means on said device carrying said pivot means, and locating means on said device predeterminedly positioning said plate means on said device and relative to said detent means, said mounting plate means being removably attached to the control device for interchange with other like mounting plate means interchangeable attachable on said device but having the pivot carrying means thereof disposed therein linearly different relative to said detent means whereby to regulate the tripping position of said arm means relative to said detent means.

2. A protective control device for automati-

cally opening an electric circuit to an electrical device, comprising in combination, shiftable circuit breaking means for closing an electric circuit to render an electrical device operative, arm means engageable with said circuit breaking means to render the same active, pivot means for pivotal mounting of said arm means, heat sensitive detent means engageable with said arm means retaining the same in position for closing of said circuit breaking means and providing tripping means for release of said arm means to provide for actuation of said circuit breaking means, and mounting means carrying said pivot means, said mounting means comprising a first mounting plate movably supported on said device for movement relative to said detent means and a second mounting plate removably attached to said first member and having means carrying said pivot means whereby said mounting plates predeterminedly position said pivot means relative to said detent means to control the tripping position of said arm means relative to said detent means.

3. A protective control device for automatically opening an electric circuit to an electrical device, comprising in combination, shiftable circuit breaking means for closing an electric circuit to render an electrical device operative, arm means engageable with said circuit breaking means to render the same active, pivot means for pivotal mounting of said arm means, heat sensitive detent means engageable with said arm means retaining the same in position for closing of said circuit breaking means and providing tripping means for release of said arm means to provide for actuation of said circuit breaking means, and mounting means carrying said pivot means, said mounting means comprising a first mounting plate movably supported on said device for movement relative to said detent means and a second mounting plate removably attached to said first mounting plate and having means carrying said pivot means whereby said mounting plates co-operate to predeterminedly position said pivot means relative to said detent means to control the tripping position of said arm means relative to said detent means.

4. A protective control device for automatically opening an electric circuit to an electrical device, comprising in combination, shiftable circuit breaking means for closing an electric circuit to render an electrical device operative, arm means engageable with said circuit breaking means to render the same active, pivot means for pivotal mounting of said arm means, heat sensitive detent means engageable with said arm means retaining the same in position for closing of said circuit breaking means and providing tripping means for release of said arm means to provide for actuation of said circuit breaking means, and mounting means carrying said pivot means, said mounting means comprising a first mounting plate supported upon a fixed pivot on said device and rotatable about said fixed pivot toward and away from said detent means, fastening means between said first plate and said device for holding said first plate immovable on said device, and a second mounting plate removably attached to said first plate and having means carrying said pivot means whereby said mounting plates cooperate to predeterminedly position said pivot means relative to said detent means to control the tripping position of said arm means relative to said detent means.

5. A protective device for automatically open-

ing an electric circuit to an electrical device, comprising in combination, shiftable circuit breaking means for closing an electric circuit to render an electrical device operative, arm means engageable with said circuit breaking means to render the same active, pivot means for pivotal mounting of said arm means, heat sensitive detent means engageable with said arm means retaining the same in position for closing of said circuit breaking means and providing tripping means for release of said arm means to provide for actuation of said circuit breaking means, and mounting means carrying said pivot means, said mounting means comprising a first member movably supported on said device for movement relative to said detent means and a second member removably attached to said first member and having means carrying said pivot means whereby said mounting members predeterminedly position said pivot means relative to said detent means to control the tripping position of said arm means relative to said detent means, said second mounting member being interchangeably attachable in identical position on said first member with other like mounting members having the pivot carrying means thereof disposed linearly different relative to said detent means whereby to regulate the tripping position of said arm means relative to said detent means by the linear position of said pivot means relative to said detent means.

6. A protective control device for automatically opening an electric circuit to an electrical device, comprising in combination, shiftable circuit breaking means for closing an electric circuit to render an electrical device operative, arm means engageable with said circuit breaking means to render the same active, pivot means for pivotal mounting of said arm means, heat sensitive detent means engageable with said arm means retaining the same in position for closing of said circuit breaking means and providing tripping means for release of said arm means to provide for actuation of said circuit breaking means, and mounting means carrying said pivot means, said mounting means comprising a first mounting plate supported upon a fixed pivot on said device and rotatable about said fixed pivot toward and away from said detent means, fastening means between said first plate and said device for holding said first plate immovable on said device, and a second mounting plate re-

movably attached to said first plate and having means carrying said pivot means whereby said mounting plates cooperate to predeterminedly position said pivot means relative to said detent means to control the tripping position of said arm means relative to said detent means, said second mounting plate being interchangeably attachable in identical position on said first mounting plate with other like mounting plates having the pivot carrying means thereof disposed linearly different relative to said detent means whereby to regulate the tripping position of said arm means relative to said detent means by the linear position of said pivot means relative to said detent means.

7. A protective control device for automatically opening an electric circuit to an electrical device, comprising in combination, shiftable circuit breaking means for closing an electric circuit to render an electrical device operative, arm means engageable with said circuit breaking means to render the same active, pivot means for pivotal mounting of said arm means, heat sensitive detent means engageable with said arm means retaining the same in position for closing of said circuit breaking means and providing tripping means for release of said arm means to provide for actuation of said circuit breaking means, and mounting means carrying said pivot means, said mounting means comprising a first mounting plate supported upon a fixed pivot on said device and rotatable about said fixed pivot toward and away from said detent means, fastening means between said first plate and said device for holding said first plate immovable on said device, and a second mounting plate removably attached to said first plate and predeterminedly positioned thereon by said fixed pivot and an attachment member and having means carrying said pivot means whereby said mounting plates cooperate to predeterminedly position said pivot means relative to said detent means to control the tripping position of said arm means relative to said detent means.
